UNITED STATES PATENT OFFICE.

PAUL M. HOTCHKIN, OF CHICAGO, ILLINOIS.

REFLECTOR.

1,225,032.

Specification of Letters Patent.

Patented May 8, 1917.

Application filed January 2, 1915. Serial No. 4.

To all whom it may concern:

Be it known that I, PAUL M. HOTCHKIN, a citizen of the United States, residing at Chicago, in the county of Cook and State of Illinois, have invented certain new and useful Improvements on Reflectors, as set forth in the annexed specification.

My invention relates to reflectors in general, that is reflectors for various forms of lighting systems, such as for the indirect illumination of rooms, for headlights of various types, for desk or reading lamps and in fact for any place where it is desired to control the direction of the light waves radiating from a suitable light source. The principal object of my invention is to construct a reflector so that the light waves may be positively directed to certain areas and confined within a desired space. Another object is to so arrange the reflecting surfaces of my device that the dazzling beam of light waves from a source of illumination such as an electric lamp of high candle power is broken up and spread out so that they may be more equally distributed within the area to be illuminated.

Still another object of my invention is the provision of a reflecting body for automobile headlights that will direct and confine the light upon the roadway and thereby avoid the glare so prevalent in such structures, the existence of which is dangerous to pedestrians as well as to drivers of machines moving in the opposite direction toward said light. The ordinances of numerous municipalities now prohibit the use of what are commonly known as "glaring headlights" and it is, therefore, an object of my invention to provide a reflector which will meet the requirements of these regulations by breaking up the beams of light waves and controlling the direction thereof.

Other objects of my invention are the provision of a reflector that is both neat and attractive in appearance, efficient in performing the particular functions for which it is designed, and which is inexpensive to manufacture so that it does not materially add to the cost of manufacture.

These and other objects I prefer to accomplish by the means and in the manner hereinafter fully described and as more particularly pointed out in the claims, reference being had to the accompanying drawings,

forming a part of this specification, in which similar reference characters indicate the same parts throughout the various figures.

Figure 1 is a vertical front elevation of one form of my improved reflector.

Fig. 2 is a top plan thereof.

Fig. 3 is a central vertical section taken on line 3—3, of Fig. 1.

Figs. 4 and 5 are views similar to Fig. 3 of a slightly modified form of reflector.

Fig. 6 is a plan view of a reflector made in accordance with my invention, the main reflector being truly spherical.

Fig. 7 is a view similar to Fig. 3 of another modified form of my reflector.

Fig. 8 illustrates one manner of forming or shaping the corners of a reflector body made in accordance with my invention.

Fig. 9 is a top plan of still another modified form of my invention in which the lower member is parabolic.

Fig. 10 is a detailed view of my reflector illustrating the manner of using the same on an indirect wall fixture.

Referring more particularly to Figs. 1, 2 and 3 of the drawings, it will be seen that my reflector comprises a shell, preferably formed of a single piece of suitable material. The lower member of this shell preferably consists of a segment 20 of a hemisphere, the outer or forward wall of which is cut away and the rear portion 21 of which curves upwardly in an arc struck from a center in advance of the vertical plane of the front of said shell. The top wall 22 of the shell constituting the base line of the hemisphere is preferably disposed in a horizontal plane and the front or forward edge thereof is straight while the rear edge conforms to the curvature of the back portion 21. At the center of the rear portion of the top and forming a continuation of the upper rear portion of the segmental member 21 a dome shaped or hollow hemispherical housing 23 is formed within which is arranged a light medium 24, preferably in the form of an incandescent electric bulb. This hemispherical housing 23 and the interior of the segmental member 21 are preferably constructed so as to reflect the light waves therefrom. The light element 24 is so disposed in the dome of housing 23 that the direct light waves proceeding therefrom will not be visible from directly in front of the reflector as will be

seen by reference to Figs. 1 and 3. The light waves, however, will proceed from the source of illumination and will also be reflected from the interior of the housing downwardly 5 to the surface of the segmental portion from which latter they will be reflected outwardly through the open front end.

In Figs. 4, 5 and 6 of the drawings the structure is substantially the same as in the figures just described with the exception that a hemispherical housing 25 is disposed farther to the rear of the front edge of the top 10 26 and the segmental member 27 has its lower portion 28 curved downwardly as well 15 as outwardly in the form of a compound curve as seen at 28. The reflector just described, when viewed from the top (Fig. 6), will be seen to have the segmental lower member 27 thereof formed of a true semi- 20 circular outline or curvature.

In Fig. 7 I illustrate a reflector constructed substantially in the same manner as shown in Fig. 3 with the exception that the upper member or housing 29, instead of being true hemispherical, is slightly parabolic 25 in shape. This is for the purpose of condensing the light against the segmental member 30 and by shielding the direct light waves through the medium of the forwardly 30 extending top 31.

As seen in Fig. 9, the reflector body 32 may be further modified by constructing it of parabolic shape and by providing the top 33 that covers the same in a manner similar 35 to that of the other structures. The upper member or housing 34 may be of either a true hemispherical or parabolic shape, as desired.

I have illustrated in Fig. 8 a refinement 40 of the reflector shown in Fig. 1 wherein the corners may be curved as shown at 32 instead of being made sharp or angular as in said Fig. 1, the remaining portion of the reflector being of any of the shapes heretofore described.

While my invention is primarily designed 45 for a reflector for automobile headlights, the structure is well applicable to indirect lighting systems where a wall bracket 35 (Fig. 50 10) is used. Heretofore the objection to wall brackets in indirect lighting has been that a portion of the light was thrown against the vertical wall and not entirely against the ceiling. With my reflector the outer edge of the top 22 will prevent the 55 waves of light reflected from the lower or outer portion of the segmental member from striking the wall, and by a proper adjustment the shadow cast by this edge may be brought into alignment with or parallel to the line at the meeting surfaces of the wall and ceiling, this directing all of the light 60 waves to the ceiling as indicated in the drawing.

65 From the foregoing description it is evi-

dent that the combined action of the light housing and the body portion of the reflector will secure the partial condensing or focusing of the light so as not only to secure its projection in the desired direction but 70 also its even distribution throughout the area to be illuminated.

While I have illustrated and described certain specified forms of my invention, it of course, will be obvious, to others skilled 75 in the art to which it pertains, that various modifications and refinements thereof are possible without materially departing from the spirit of my invention. I therefore desire it understood that all such modifications and refinements are included within the scope of my invention as expressed in the claims.

What I claim as new is:—

1. A device for projecting light comprising a sector of a concave reflector provided with a supporting plate and a supplemental concave reflector supported on said plate, the axis of which latter reflector is at right angles to the axis of the first named reflector. 85

2. A device for projecting light comprising a sector of a hemispherical reflector having a plate closing said sector, and a supplemental reflector supported on said plate 95 the axis of which latter reflector is at substantially right angles to the axis of the first named reflector.

3. A reflecting device comprising a substantially concave reflector, a top plate or 100 shield extending from the front to the rear thereof and provided with an opening, and a concave reflector of relatively small dimensions mounted in said opening and adapted to reflect a portion of the light 105 waves from a suitable light source through said opening upon said first mentioned reflector and a source of light mounted in said smaller reflector. 110

4. A reflecting device comprising a substantially concave reflector, a top plate extending from the front to the rear thereof and provided with an opening, and a concave reflector of relatively small dimensions mounted in said opening the axis of which is 115 at right angles to said first mentioned concave reflector and adapted to reflect a portion of the light waves from a suitable light source through said opening upon said first mentioned reflector, and a source of light 120 mounted in said smaller reflector.

5. A device for projecting light comprising a sector of a concave reflector provided with a supporting plate and a supplemental concave reflector supported on said plate the 125 axis of which latter reflector is at substantially a right angle to the axis of the first mentioned reflector.

6. A reflecting device comprising a substantially concave reflector, a plate extend- 130

ing from the front to the rear thereof and provided with an opening, and a concave reflector of relatively small dimensions mounted in said opening and adapted to reflect a portion of the light rays from a suitable light source through said opening upon said first-mentioned reflector, and a source of light within said device.

7. The combination with a reflector of substantially concave curvature in cross-section, of a plate the curvature whereof conforms to the curvature of said reflector, and a concave reflecting surface mounted on said plate and adapted to reflect light rays across the axis of said first named concave

reflector to be projected forwardly out of the latter.

8. The combination with a reflector of concave curvature, of a plate having an edge the curvature of which conforms to the curvature of said reflector and being provided with an opening adjacent its rear edge, and a concave reflector on said plate above said opening.

In testimony whereof I have hereunto set my hand, this 29th day of December, 1914.

PAUL M. HOTCHKIN.
